WEATHER VANE DESK ORNAMENT

Richard A. Donges, Inglewood, Calif., assignor to Peter Pepper Products, Inc., Lomita, Calif., a corporation of California

Application February 24, 1958, Serial No. 49,771

Term of patent 7 years

(Cl. D52—9)

I claim:

The ornamental design for a weather vane desk ornament, substantially as shown.
